UNITED STATES PATENT OFFICE.

THOMAS SPOONER, OF EDGEWOOD, PENNSYLVANIA, ASSIGNOR TO WESTINGHOUSE ELECTRIC & MANUFACTURING COMPANY, A CORPORATION OF PENNSYLVANIA.

MAGNETIC PYROMETER.

Application filed August 14, 1926. Serial No. 129,277.

My invention relates to temperature-indicating and control devices and particularly to magnetic pyrometers.

An object of my invention is to provide a temperature-indicating and control device that shall be responsive to changes in the magnetic properties of a core associated therewith in response to changes in temperature thereof.

Another object of my invention is to provide a temperature-indicating and control device that shall be effective to produce large indications for small changes in temperature.

In practicing my invention, I provide a magnetic core member and a plurality of coils wound thereon in inductive relation to each other. The coils and core member may be considered as a transformer. One of the coils is energized from a source of alternating current. I provide also a temperature-indicating and control instrument which is provided with voltage and current coils so connected to the coils of the transformer that the instrument will indicate the temperature of a body and be adapted to control a circuit-interrupting device in accordance with the temperature of the body. The core member which I employ may be made of a plurality of parts, each of which has a different re-

calcent point.

In the single sheet of drawings, Fig. 1 is a diagrammatic view of the device embodying my invention; and

Fig. 2 is a view illustrating the device shown in Fig. 1 as applied to a control circuit for controlling an electric furnace.

In Fig. 1, a temperature-indicating and control device 11 comprises a transformer 12 and an indicating and control instrument 13. The transformer 12 comprises a core member 14 and a pair of coils 15 and 16 wound thereon. The temperature-indicating and control instrument 13 is provided with a pair of relatively movable coils 17 and 18 (see Fig. 2), a movable indicator and contact member 19, and a scale 20 calibrated in degrees of temperature. The coils 17 and 18 are so connected to the coils 15 and 16 as to cause a deflection thereof when energized from a source 21 of alternating current. A switch

member 22 is employed for controlling the temperature-indicating and control device 11.

Fig. 2 of the drawings illustrates the application of my temperature-indicating and control device 11 to the temperature control of an electric furnace 23. The furnace 23 is provided with resistor members 24 which are energized from an electrical-energy source 25. A control device 26 comprises a circuit 55 interrupter 27 and an actuating mechanism 28, the latter comprising a coil member 29, a core member 30 actuated thereby, a pair of links 31 and 32, and a restraining spring 33. The coil member 29 is controlled by the instrument 13 and is energized upon the engagement of a contact member 34, insulatedly mounted on the member 19, with a stationary contact member 35.

In the particular application of the device 11, as illustrated in Fig. 2, the transformer 12 is provided with a protecting cover member 36 which encloses the core member 14 and the coils 15 and 16. The core member 14, illustrated in Fig. 2, comprises a plurality of portions 37, 38 and 39. The portions 37, 38 and 39 are of magnetic material but have different recalcenscent points at which the respective portions become non-magnetic.

The operation of the device illustrated in Figs. 1 and 2 is dependent upon the magnetic properties of the core member 14. Since the coil 15 is energized from a source of alternating current, the coil 16 will have a voltage induced therein which will be dependent upon the number of turns in the two coils and the magnetic density in the core 14. As the temperature of the core member 14 increases, the magnetic density thereof will decrease, and the induced voltage of the coil 16 will also decrease.

Since the instrument 13 is provided with a restraining spring 41, the coils 17 and 18 will deflect in accordance with the decrease of the energy generated in the coils 16. As the temperature increases, the energy consumed in the core member 14 will decrease until the movable member 19 has caused the contact members 34 and 35 to engage each other to energize the coil 29. Upon energization of

the coil 29, the circuit interrupter 27 will be disengaged from the contact members 42 and 43, thereby deenergizing the resistor members 24.

5 Since the coils of the instrument 13 and the coils of the transformer 12 are in circuit with the source 21 of alternating current, the energy generated or consumed by the core member 14, and the voltage generated in 10 the coil 16 will increase upon a decrease in the temperature of the core member 14, because the magnetic properties thereof will again become active at the lower temperature. By employing a plural-part core member 14, 15 as illustrated in Fig. 2, each of the parts having different temperature at which it becomes non-magnetic, the instrument 13 will have a larger range of operation.

In the event that the losses in the core member 14 are not sufficient to produce the desired wattmeter reading, a suitable resistance may be inserted in circuit with the primary coil 14 of the transformer 12.

By my invention, I provide a temperature-indicating and control device of the magnetic-pyrometer type in which the operation of the indicating portion of the instrument is effected by the magnetic induction of a transformer in which the core thereof gradually loses its magnetic properties upon increases in temperature.

Various modifications may be made in my invention without departing from the spirit and the scope thereof. I desire, therefore, 35 that only such limitations shall be placed thereon as are imposed by the prior art and the appended claims.

I claim as my invention:

1. A temperature-indicating device comprising a plural-part metallic core member, 40 the parts thereof having different recalcence points, a pair of coils inductively wound thereon, one of said coils being energized from a source of alternating current and 45 means connected in circuit with said coils for indicating the energy consumed in said core member in accordance with the temperature thereof.

2. A temperature-indicating device comprising a plural-part metallic core member, 50 the parts thereof having different recalcence points, a plurality of coils wound thereon in inductive relation to each other, one of said coils being energized from a source of 55 alternating current, and an instrument having voltage and current coils connected in circuit with said first named coils for indicating the temperature to which said core member may be subjected.

60 3. The combination with an indicating and control instrument comprising relatively movable voltage and current coils, and a movable contact member adapted to be actuated by one of said coils to engage a stationary contact member, of means adapted to be subject-

ed to the temperature of a body to be controlled comprising a plurality of coils, a plural-part magnetic core member therefor, the parts thereof having different recalcence points, said coils being inductively coupled 70 and so connected to said voltage and current coils as to actuate the movable contact member in accordance with the energy consumed in said core member when one of said coils is energized by a source of alternating current. 75

4. A temperature-indicating and control device comprising a plural-part core member, the parts thereof having different recalcence points, a plurality of coils mounted thereon in inductive relation, one of said coils 80 being energized from a source of alternating current, and an instrument comprising a plurality of relatively movable voltage and current coils, and a pair of contact members controlled thereby, said voltage and current coils 85 being so connected to said first named coils as to cause relative movement of said voltage and current coils.

5. A thermal relay, comprising a core member, a plurality of coils wound thereon in inductive relation one to another, a protective device disposed around the coils and core member, and a control and indicating instrument comprising relatively movable voltage and current coils so connected to said plural- 90 ity of coils as to actuate said instrument when one of said plurality of coils is energized from a source of alternating current in accordance with a temperature to which said core member may be subjected. 100

6. A thermal relay for indicating and controlling the temperature of a body to be heated comprising a transformer having a plural-part magnetic core, said parts having different recalcence points, said transformer being subjected to the temperature of the body to be controlled, and means having voltage and current coils so connected to the coils of said transformer as to indicate the temperature of said body and to actuate said relay. 105

7. In a thermal protective device, a core member comprising sections having different magnetic characteristics, a plurality of windings thereon, and means connected to said windings responsive to temperature changes 110 in the core member.

8. In a thermal protective device, a core member comprising sections having different metallurgical compositions, a source of heat energy associated therewith, magnetizing means operating therewith, and means controlled by said magnetizing means when a predetermined thermal condition obtains in the core member. 120

9. In a thermal protective device, a core member comprising sections having different magnetic transformation points, said core member being subjected to a thermal condition to be controlled, windings on said core member having impedances responsive to 125 130

said transformation points, and circuit control means connected to said windings so as to be controlled thereby.

10. In a thermal protective device, a core member comprising sections having different points of critical magnetic permeability, windings thereon, and circuit control means

connected thereto and adapted to be actuated by changes in said permeability.

In testimony whereof, I have hereunto subscribed my name this 11th day of August, 1926.

THOMAS SPOONER.
